US0D1113160S

(12) **United States Design Patent** (10) **Patent No.:** **US D1,113,160 S**
(45) **Date of Patent:** **** Feb. 17, 2026**

(54) **EARBUD CASE**

(71) Applicant: **Amazon Technologies, Inc.**, Seattle, WA (US)

(72) Inventor: **Emmanuel Laffon de Mazieres**, Danville, CA (US)

(73) Assignee: **Amazon Technologies, Inc.**, Seattle, WA (US)

(**) Term: **15 Years**

(21) Appl. No.: **30/005,276**

(22) Filed: **May 23, 2025**

Related U.S. Application Data

(60) Continuation of application No. 29/913,247, filed on Sep. 28, 2023, now Pat. No. Des. 1,081,142, which is a division of application No. 29/828,130, filed on Feb. 24, 2022, now Pat. No. Des. 1,010,313.
